(54) **SPINNING COTTON & SILK**

(76) Inventor: **Samuel P. Mason**

Samuel P. Mason, of Hellingly, Ct.
Letters Patent

The Schedule referred to in these Letters Patent and making part of this document containing a description in the words of the said Samuel P. Mason himself of his improvement in the machine for spinning Cotton and Silk.

To all to whom these presents shall come: - Be it known that: -
I, Samuel P. Mason of Hellingly in the County of Windham and State of Connecticut have invented a new and useful improvement in the art of spinning Cotton and Silk consisting of a Flyer of a cylindrical form and a Flyer to be applied to any spinning frame used for spinning Cotton or Silk, and its construction is to roll with less resistance from the atmosphere than any flyer now in use and consequently to be capable of greater speed and to require less power and that the following specification including what referring to the drawings and diagrams hereto annexed contains a full and exact description of the construction and operation and operation of the said machine as invented and improved by me -

A cylinder marked A (andingson) made of brass copper iron or many other suitable material 2 $\frac{1}{2}$ inches to 3 $\frac{1}{2}$ inches in length or of such length as to suit any length of bobbin that the manufacturer may have proper to use and the diameter of the cylinder made to suit the size of the bobbin, any from one to three inches. The end of this cylinder is a bottom or head to which a steel or iron hollow spindle (B) is either secured or brazed, from 2 $\frac{1}{2}$ to five inches in length which may in a step (C) and has a bearing (D) on the top and close to the bottom of the cylinder, and has on it a wheel (E) in which a band passes to give motion to the Flyer. Through the above described hollow spindle passes a cast steel spindle (F) up through the center of the cylinder on which is fixed a wood or bone

button (6), which supports the bobbin (56). The cast steel spindle last mentioned has a transverse motion, will lift up and down which regulates the falling and laying of the yarn on the bobbin. At the top of the cylinder which stands perpendicular to the small hooks are attached two small metal wires, one for the purpose of giving twist to and guiding the thread on the bobbin. The above mentioned spindle mechanism is not differing essentially from many spinning machines used and claimed as a part of the invention.

The witness affirms that he has fully described his invention this 16th day of December A.D. 1833.
